UNITED STATES PATENT OFFICE.

GEORGE J. KOLLAR, OF WHITING, INDIANA.

BATH DEVICE.

Application filed October 19, 1921. Serial No. 508,708.

To all whom it may concern:

Be it known that I, GEORGE J. KOLLAR, a citizen of the United States, residing at Whiting, in the county of Lake and State 5 of Indiana, have invented certain new and useful Improvements in Bath Devices, of which the following is a specification.

This invention relates to devices for use in bathing the human body and has for its 10 object to provide in one instrument a cleaning element, and an element for storing cleansing fluid in such relationship that the storage element will provide a continuous supply of the cleansing fluid to the cleansing 15 element during the necessary period of use.

Another object of the invention is to provide an instrument of this character which will be sufficiently flexible to permit ready application to various parts of the body, 20 and which will enable any one to effectually cleanse the back and other portions not readily reached with the hands.

Further objects of the invention will become apparent as the description is read in 25 connection with the accompanying drawing showing a selected embodiment of the invention, in which—

Fig. 1 is a longitudinal sectional view of the device; and

Fig. 2 is an inverted plan view.

In manufacturing the device, I preferably use a body or backing 10 of material having sufficient flexibility to make the cleansing portion of the device readily applicable to 35 all parts of the body. As shown, this backing may be in the form of an elongated strip having a handle at each end and carrying the cleansing and storage elements along one side. The handles may be integral with 40 the backing and of any suitable form, but for example I have shown them as including a grip 11 carried on a shaft 12 spanning the yoke 13 which is connected by a swivel 14 to the clip 15 secured to the backing by 45 rivets 16.

In the present embodiment a portion of a backing adjacent to each end is fitted with an absorbent element 17 as sponge, or the like, secured to the backing in any suitable 50 manner, and of a shape convenient to particular use or particular taste. The prin-

cipal requirement of these elements is that they shall readily absorb a considerable quantity of water or soapy water and feed it out during the use of the device at a rate 55 depending upon the pressure applied. Between these sponges is a length of brush 18 which may be in the form of bristles or other cleansing devices which may be preferred by the individual. As shown, the 60 bristles are set in a rubber strip 19 which is secured to the backing 10.

This arrangement of brush and sponge elements is very satisfactory in use, but it is to be understood that it is within the 65 scope of my invention to vary the size and relative position of these elements quite widely. Very good results can be obtained by providing a plurality of brush elements alternating with sponge elements. While I 70 have shown the cleaning and absorbing element on one side of the device only, this is optional, for some may prefer to have both sides equipped with bristles of different stiffness, or different character. 75

In use, the device may be dipped in soapy water or first wet with water and then supplied with soap to either the sponges or bristles, or to both, and then applied to the body with the pressure or speed suitable to 80 individual taste. It may be used on the front portions of the body in much the manner of ordinary bath equipment, and then applied to the back by taking one handle in each hand and using it in the fashion customary 85 with the bath towel. The sponges will store a suitable quantity of soap solution, or soapy water and will feed it out slowly or rapidly, depending upon the pressure applied and keep the body and the bristle portion well 90 supplied with the cleansing fluid, and thereby facilitate the bath. The device as shown can be used in such a manner that the liquid pressed out of one sponge may be, to a large extent, taken up by the other sponge, and 95 on the reverse stroke of the device, the liquid may be again pressed out and again absorbed by the first sponge.

I am aware that changes in the form and proportion and arrangement of parts of my 100 invention may be made without departing from the spirit or sacrificing any of the ad-

vantages thereof and I therefore reserve the right to make all such changes as fairly fall within the scope of the following claim:

5 I claim:

In a bath device, a flexible backing, a bristle brush secured to one side of said back-

ing and sponges secured to the same side of said backing at opposite ends of said bristle brush whereby said sponges and brush are adapted to alternately act upon the same surface when the device is moved back and forth.

GEORGE J. KOLLAR.
